Patented Oct. 19, 1920.

INVENTOR
Albert Neal,
By Frank W. Werner,
ATTORNEY.

UNITED STATES PATENT OFFICE.

ALBERT NEAL, OF KOKOMO, INDIANA.

LIFTING-JACK.

1,355,842.

Specification of Letters Patent. Patented Oct. 19, 1920.

Application filed October 2, 1918. Serial No. 256,496.

To all whom it may concern:

Be it known that I, ALBERT NEAL, a citizen of the United States, residing at Kokomo, in the county of Howard and State 5 of Indiana, have invented certain new and useful Improvements in Lifting-Jacks, of which the following is a specification.

A demand has arisen for a lifting-jack by which a wheel of a motor car can easily 10 be raised a distance so that the face of the tire will clear the ground, and by which the load can be instantly dropped by reason of the cushioning effect afforded by the pneumatic character of the tire, so that 15 the tedious operation of gradually letting the car down is obviated.

The present invention relates to the above class of lifting-jacks, and one of the objects 20 of the invention consists in the provision of a lifting-jack of the above character by which a motor car, or similar load, can be easily and quickly raised the desired height and at the conclusion of making repairs, 25 such, for instance, as changing a tire, the load can instantly be dropped, thereby effecting a considerable saving of time than by the use of a jack whereby the load must be lowered through successive steps.

A further object of the invention consists 30 in the provision of a lifting-jack of the above character in which the lifting-bar holds all of the acting parts against accidental displacement, together with a single means for preventing accidental displacement 35 of said lifting-bar.

A still further object of the invention consists in the provision of a lifting-jack of the above character which is simple in construction, efficient in operation, and cheap 40 to manufacture.

I accomplish the above objects of the invention, and such others as may appear from a perusal of the specification and claims, by means of the construction illustrated in the accompanying drawing forming 45 a part hereof, in which—

Figure 1 is a central vertical sectional view of the lifting-jack housing, showing the movable parts in elevation. Fig. 2 is a view similar to Fig. 1, except that the movable parts of the jack are shown as occupying a changed position. Fig. 3 is a sectional view on the line 3—3 in Fig. 1. Fig. 4 is a fragmentary detail front elevation of the 50 lifting-jack housing. Fig. 5 is a cross sec-

tional view of the lifting-bar, on the line 5—5 in Fig. 1. Fig. 6 is a front elevation, on an enlarged scale, of the upper end of the inner pawl and swinging cam-arm.

Referring to the drawings, 10 represents the lifting-bar of the device, and this bar is provided in one edge with a series of teeth 11, and the opposite edge of the bar is cut away so as to form a pair of longitudinal parallel recesses 12, which are separated by a rib 13, and recesses 12 are closed at their lower ends by means of the shoulder 15, the object of the shoulder being hereinafter described. Lifting-bar 10 has vertical movement through a passageway 16 in housing 17 of the jack, and passageway 16 is formed by the side walls of housing 17, outer wall 18, and inner wall 19. Lifting-bar 10 is moved vertically by means of a lever 20, and this lever is provided with trunnions 21 which are introduced into housing 17 through internal passageways 22, the latter terminating in laterally disposed recesses 23 (Fig. 1) the closed ends of which are adapted to receive and form bearing points adapted to receive the trunnions 21 on lever 20. The inner end of lever 20 is provided with a pair of eccentrically located recesses 25 and 26 which form seats for the bar actuator pawls 27 and 28, and these pawls are arranged relatively to the axis of trunnions 21 so that when lever 20 is oscillated said pawls will alternately be moved upwardly and downwardly and thereby intermittently move lifting-bar 10 upwardly. Pawls 27 and 28 are pivotally connected with lever 20 by means of the cylindrical bosses 30 (Fig. 3) which enter suitable apertures in a rib 31 formed along one of the side edges of said lever. With the heretofore described construction and arrangement of parts, as lever 20 is moved upwardly into the position indicated by the dotted line in Fig. 1, pawl 27 moves downwardly so as to engage the succeeding tooth in lifting-bar 10 while, at the same time, pawl 28 is engaged with one of the teeth 11 and is moving bar 10 upwardly.

On the downward stroke of lever 20 pawl 28 is disengaged from teeth 11 and moves downwardly while pawl 27 is engaged with one of the teeth 11 and is moving bar 10 upwardly. Pawls 27 and 28 are moved alternately into and out of engagement with

teeth 11 on lifting-bar 10 through the instrumentality of a fixed cam 35 carried by pawl 28 and a swinging-cam 36 pivotally connected to and moving with pawl 27. 5 The oval shaped character of the opposing faces of cams 35 and 36 controls the alternate engagement and disengagement of the free end of pawls 27 and 28 in the following manner. When lever 20 is elevated, the 10 mounting of pawl 28 relatively to the axis of trunnions 21 causes said pawl to move upwardly and with it lifting-bar 10 the distance of one of the teeth 11, and during this movement of pawl 28 the integral cam 15 35 is carried upwardly a corresponding distance. During this upward travel of pawl 28, swinging-cam 36 moves downwardly with pawl 27 and rides over the oval face of cam 35 and pulls swinging-cam 36 in a direction to cause pawl 27 to be disengaged. 20 When pawl 27 nears the end of its downward travel it is free to move into engagement with teeth 11 by means of the additional clearance afforded by the rounding 25 off character of the opposing faces of cams 35 and 36. On the downward stroke of lever 20 pawl 27 is carrying the load and moves upwardly carrying bar 10 with it, while the pivotal mounting of swinging- 30 cam 36 is free to ride over the oval face of cam 35 without affecting the movement of or disengaging pawl 27 from teeth 11. During this latter operation of lever 20 pawl 28 moves downwardly free of teeth 11. 35 The range of oscillation of lever 20 in raising lifting-bar 10 upwardly in successive steps so that the movable parts of the jack will function properly is regulated by means of a notch 40 cut into the inner wall 40 of housing 17, as clearly shown in Fig. 4. The free end of lever 20 is hollow to receive an operating handle 41 so that the desired leverage can be secured and whereby handle 41 can be removed to enable the 45 jack to be placed within the length of an ordinary tool-box, such as forms a part of the equipment of all motor cars. The inner end of handle 41 is widened, as at 42, (see Fig. 3) and between the widened portion 42 and the major portion of the handle 41 where it rests within the hollow portion 50 of lever 20 it is formed wedge-shaped. This construction affords the necessary clearance to permit handle 41 to be moved and shift 55 the widened portion 42 laterally a sufficient distance to cause the edge of portion 42 to project beyond the edge of lever 20 and into notch 40, thereby confining the throw of lever 20 within the length of said notch. 60 The inner end of handle 41 is properly located within the hollow portion of lever 20 so as to hold the widened portion 42 within notch 40 by means of an integral lug 44 formed on the underside of portion 42 and 65 this lug is shifted laterally from one side to

the other of a positioning lug 45 arranged centrally in the end of the hollow portion of lever 20 when handle 41 is oscillated. When lug 44 is placed on one side of the 70 positioning lug 45 the side edge of the widened portion 42 projects beyond the limits of lever 20 and moves within notch 40 in housing 17. When it is desired to drop the load, handle 41 is moved longitudinally a sufficient distance to move lug 75 44 clear of positioning lug 45, and after shifting lever 41 laterally to bring lug 44 on the opposite side of positioning lug 45, handle 41 is again moved inwardly. In this last mentioned position the widened 80 portion 42 will project beyond the opposite side of lever 20 and into a notch 47 (Fig. 4) which affords a longer throw of the handle 41, and as the latter is moved upwardly an abnormal distance pawl 27 will 85 be lowered an abnormal distance and bring the hook on its free end into engagement with inclined face 49 on inner wall 19 causing said pawl to be disengaged from teeth 11. As pawl 27 moves backward in disengaging from teeth 11, under the influence of inclined face 49 the outer face of said pawl contacts the adjacent face of cam 35 and disengages pawl 28 from teeth 11, thereby allowing lifting-bar 10 to freely drop. 90

95 It will be noted in examining Fig. 1 that lifting-bar 10 may extend below housing 17 to enable a load to be lifted a greater distance than would otherwise be possible if said bar was nested wholly within the housing 17. In this case an auxiliary block is employed to form a base for the housing 17.

100 By means of the hereinbefore described construction and arrangement of parts, lever 20 and its connected pawls 27 and 28 105 are held against accidental displacement while lifting-bar 10 is in its proper operative position, and the latter is limited in its travel and against accidental displacement by means of the flanged-head 50 and a set-screw 51 which projects into one of the longitudinal recesses 12 and contacts shoulder 110 15 formed on the lower end of lifting-bar 10.

115 Having thus fully described my said invention, what I desire to secure by Letters Patent, is—

1. A lifting jack comprising a housing having a passageway therethrough, a toothed lifting-bar having movement 120 through said passageway, an oscillating lever arranged in said housing, an inner and an outer pawl arranged to pivotally connect with the lever on the opposite sides of its pivot and alternately engaging the 125 toothed bar by the rocking of the lever, a swinging cam carried by said inner pawl and a fixed cam carried by the outer pawl and arranged for moving the swinging cam outwardly and disengaging the inner pawl 130

when the latter moves downwardly of said lifting-bar.

2. A lifting jack comprising a housing having a pair of internal notches of different lengths, a toothed lifting-bar having movement through said housing, an oscillating lever arranged in said housing, an inner and an outer pawl arranged to pivotally connect with the lever on opposite sides of its pivot and alternately engaging the toothed bar by the rocking of said lever, a handle arranged in said lever and susceptible of being shifted laterally to cause the inner end of the handle to project outside the lever and into the short notch in the housing for limiting the throw of the pawl to the distance the teeth in the lifting bar are spaced apart.

3. A lifting jack comprising a housing having a pair of internal notches of different lengths, a toothed lifting-bar having movement through said housing, an oscillating lever arranged in said housing, an inner and

an outer pawl pivotally connected to said lever on opposite sides of its pivot for alternately moving said pawls into engagement with said lifting-bar when the lever is oscillated, a laterally movable handle arranged in said lever for shifting the inner end of the handle into the short or long notch and thereby limit the throw of the lever to move the pawls the distance the teeth in the lifting-bar are spaced apart or for moving the pawls an abnormal distance for contacting a stationary cam and effect the disengagement of the pawls from the teeth in the bar, and a stationary cam arranged in the housing for contacting and effecting the disengagement of the free end of the inner pawl from the tooth lifting-bar when the lever is depressed an abnormal distance.

In witness whereof I have hereunto set my hand and seal at Indianapolis, Indiana, this 28th day of September, A. D. one thousand nine hundred and eighteen.

ALBERT NEAL. [L.S.]
